UNITED STATES PATENT OFFICE.

WILLIAM T. HORMES, OF CATONSVILLE, MARYLAND.

DESIGN FOR A COMBINATION CORNICE AND PILASTER.

Application filed November 2, 1928. Serial No. 28,732. Term of patent 7 years.

To all whom it may concern:

Be it known that I, WILLIAM T. HORMES, a citizen of the United States, residing at Catonsville, in the county of Baltimore, State of Maryland, have invented a new, original, and ornamental Design for a Combination Cornice and Pilaster, of which the following is a specification, reference being had to the accompanying drawing, forming part thereof.

Figure 1 is a front elevation of a combination cornice and pilaster, illustrating the design of the invention. Figure 2 is a detail perspective view thereof. Figure 3 is a cross-sectional view taken on the line 3—3 of Figure 1.

I claim:

The ornamental design for a combination cornice and pilaster, as shown.

WILLIAM T. HORMES.
